UNITED STATES PATENT OFFICE

2,637,794

TEMPERATURE ALARM SWITCH

James T. Grotenhouse, Orange City, Iowa

Application May 28, 1951, Serial No. 228,689

1 Claim. (Cl. 200—140)

1

My invention pertains to an alarm switch.

An object of my invention is to provide a switch having an adjustable arrangement wherein the switch will operate below a pre-determined point, and will further operate above a pre-determined point, leaving a certain pre-selected range in which the alarm will not operate, the adjustment for the above purposes being relatively simple.

A further object of my invention is to provide the above mentioned in an economical construction.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a plan view of the switch base with the cover being removed,

Figure 2 is a sectional elevation of the switch and casing, and

Figure 3 is a detail.

My invention contemplates the provision of a switch which is responsive to temperature conditions for use in brooders, or other locations and which switch will operate an alarm at pre-determined temperatures, and yet leaving a certain range of temperature which will not operate the said alarm.

I have used the character 10 to designate the base of the switch, the character 11 indicating a suitable outer casing having the openings 12.

Attached to the base 10 are the members 13 to which is pivoted at 14 the U-shaped lever 15. Pivoted at 16 to the lever 15 is a further U-shaped lever 17 which includes the transverse bar 18 attached thereto, to which is secured the spring 19 which is attached at 20 to the base 10. The member 17 includes an opening 21 through which the spring 19 can pass. A holder member 22 is secured to the base 10 and mounted in the member 22 is a micro-switch 23 which is suitably connected to any alarm circuit which switch includes the button 24, the switch being normally closed and completing the circuit when the button 24 is in its upper position.

Threadably engaging the top wall 25 of the member 15 is the vertically positioned stud 26 having the knurled end 27 and the lock-nut 28, the lower end 29 of the stud 26 being adapted to engage the upper end 30 of the temperature responsive bellows 31, which expands according to the temperature.

Also threadably engaging the top wall 25 of the member 15 is a further stud 32, the end 33 of which is adapted to bear against the lower wall of the lever 17 as shown, the stud 32 having the knurled end 34 and lock-nut 35. The holder member 22 includes the inner flange 36 having the upper edge 37.

The device operates in the following manner.

The stud 26 is provided for the purpose of establishing the alarm point below a pre-determined temperature. For instance as shown in Figure 2 the alarm circuit is open, assuming that the end 30 of the bellows 31 has just contacted the lower end 29 of the stud 26, this causing the lever member 15 to pivot upwardly and at the same time causing the spring 19 to pivot the member 17 downwardly providing means for depressing the button 24 and keeping the circuit open. At any temperature lower than this the outer end 38 will swing upwardly out of engagement with the button 24 due to the fulcrum action at the point 37, thereby operating the alarm.

When the temperature increases beyond a pre-determined point, since the member 17 will abut against the end 33 of the stud 32, the bellows 31 will carry the entire unit upwardly as shown in Figure 3, thereby operating the alarm also. It will be noted that the adjustable positioning of the stud 32 provides any desired variation of temperature range within which the alarm will not be operated as will now be explained. For instance if the stud 32 is rotated, bringing the point 33 to a higher level, there will correspondingly be a longer range of action of the lever member 17 as it fulcrums over the edge 37, thereby providing non-operation of the switch, or in other words maintaining the switch in opened position for a relatively longer interval.

Correspondingly, by rotating the stud 32 downwardly the lever action will not be over as long a period of time, thereby effecting a shorter temperature range of non-operation. In this manner, the heated structure can be maintained at a certain temperature range without operating the alarm, beyond which point however the alarm will operate.

It should be noted that the spring 19 has the tendency of pulling the end 38 downwardly at all times.

It will now be noted that I have provided all of the advantages mentioned in the objects of my invention with further advantages being readily apparent.

Some changes may be made in the construction and arrangement of the parts of my invention

without departing from the real spirit and purpose of my invention, and it is my intention to cover by my claim any modified forms of structure or use of mechanical equivalents which may be reasonably included within their scope.

I claim as my invention:

A temperature alarm switch comprising an expansible temperature responsive member, a pivoted lever, a vertically positioned lengthened stud threadably engaged with said lever, the lower terminal of said stud being adapted to engage said temperature responsive member at a pre-determined temperature, and whereby adjustable movement of said stud will correspondingly vary said engagement, a micro-switch, a further lever pivoted to said lever for operating said micro-switch, said micro-switch providing means for actuating an alarm circuit and being normally in closed position, said micro-switch including an operating button, one end of said further lever being adapted to engage said button, a flange member upon which said further lever fulcrums

15 incidental upon movement of said levers, means for adjustably positioning said further lever to maintain said switch button in switch opening position at a predetermined interval including a further stud threadably engaging said pivoted lever, the lower terminal of said further stud being adapted to engage the other end of said further lever, a base member, a spring attached between said base member and said further lever. 10 adjustable positioning of said further stud vertically causing said switch to be opened during said predetermined interval corresponding to the fulcrumming interval between said further lever and said flange.

15 JAMES T. GROTHOUSE.
